[57] **CLAIM**

The ornamental design for a bottle, as shown and described.

DESCRIPTION

FIG. 1 is a perspective view of a bottle, embodying my new design;

FIG. 2 is a front elevation thereof, the rear elevation being a mirror image thereto;

FIG. 3 is a side elevation view thereof, viewed from the left of FIG. 2;

FIG. 4 is an opposite side elevation view thereof, viewed from the right of FIG. 2;

FIG. 5 is a top plan view thereof; and

FIG. 6 is a bottom view thereof.
